UNITED STATES PATENT OFFICE.

PHELPS M. FREER, OF DETROIT, MICHIGAN.

ENGINE COMPRESSION REGULATOR.

Application filed January 20, 1921. Serial No. 438,629.

To all whom it may concern:

Be it known that I, PHELPS M. FREER, a citizen of the United States of America, residing at Detroit, in the county of Wayne 5 and State of Michigan, have invented certain new and useful Improvements in Engine Compression Regulators, of which the following is a specification, reference being had therein to the accompanying drawings.

10 This invention relates to engine constructions and method of operating same and refers more particularly to an engine compression regulator or system.

In internal combustion engines particularly those operated at variable speed such as the ordinary automobile, airplane, motor-boat or the like type of engines the degree of compression in the engine cylinders is limited from a practical standpoint by the 20 compression that can be used at speeds below the maximum. Therefore in designing the engine it has been considered necessary to use a compression space of a size which will be practical for the various speeds.

25 The present invention contemplates a radical departure from the prior art in that the engine is initially designed with a relatively small compression space thus producing a higher degree of compression than is practical with engines and systems of operation now in use. I then provide a novel mechanism for regulating the maximum compression at the various speeds so that when operating at the various speeds the 30 proper degree of compression will be maintained which compression regulating system can be employed either with or without the ordinary speed governor. The invention also resides in the novel arrangement for

35 providing preferably automatically a different degree of compression in starting the engine when cold and in the operation of the engine after being heated up. Further objects of the invention are to provide a construction and system which can be economically installed and which can be readily adapted to the types of engines now in use without material change or alteration in the construction thereof. Other features of the 40 invention reside in the novel combinations of the different control mechanisms and in such further features of construction and arrangements of parts and operations as will more fully hereinafter appear.

45 50 55 In the drawings:

Figure 1 is a diagrammatic fragmentary

vertical section illustrating one embodiment of my invention;

Figure 2 is an enlarged detail view of the automatic temperature control adjustment. 60

Describing first in detail the particular embodiment of my invention shown in Figs. 1 and 2, A designates one of the cylinders of an internal combustion engine having the water jacket A' providing cooling water 65 spaces A². In this cylinder there is arranged to reciprocate the ordinary piston B connected by the piston rod B' to the crank shaft B². B designates the intake manifold having a connection C' to the carburetor D. 70 The latter may be of any known construction, but as shown, is of the type in which the air is admitted through the inlet D' and passing through the bowl D² picks up fuel from the supply nozzle D³, the latter being controlled 75 by a needle valve D⁴. The amount of air and gas mixture is controlled by a butterfly valve E which is operated by a hand-controlled lever E', these parts being of ordinary construction and forming no part of the present 80 invention except in their relation and combination with the compression control mechanism.

In addition to the butterfly valve E the passageway C is provided with a second butterfly or throttle valve F which is operated by a rocking of an arm F', which in turn is moved toward its open position by a cam G and normally held toward its closed position by a spring F². The cam G turns on a pivot 85 G' carried by a vertically adjustable rod or support G², the construction and operation of which is later described in detail. For rocking the cam G about its pivot there is employed a vertically adjustable sleeve H, 90 which at its upper end engages the projection G³ on the cam G. The sleeve H is telescopically mounted on a governor shaft I which, as it is rotated at variable speeds, causes the arms I² to be thrown outwardly 95 100 by centrifugal force as the speed of the shaft I increases, thus lifting the sleeve H which in turn lifts the projection G³ on the cam G and rocks the latter about its pivot G'. Thus as the speed of the shaft I increases 105 the cam G is rocked to a position which will raise the outer end of the rod F' and rock the valve F toward its open position. As the speed of the shaft I decreases the cam G will be returned toward its lower position 110 thus permitting the spring F² to draw the rod F' downwardly and variably restrict the

opening past the valve F. This shaft I is driven in timed relation to the speed of the engine and while the intermediate connection may be from a timer shaft or any other part of the engine I have shown it in the drawings as operated from the crank shaft B² by means of a series of bevelled gears J, J', J² and J³. By this novel arrangement above described, the amount of air and gas mixture passing to the cylinders and thus the compression desired at each speed is automatically governed in accordance with the speed of the engine. It is therefore possible to have a very small compression space B³ giving more power if desired but preventing too high compression. In fact in this manner it is possible to increase the maximum speed and power, but if desired, this control system can of course be used in connection with a standard form of governor which will control the engine speed. It is to be especially noted, however, that the compression regulator performs an entirely different function than the control of the maximum speed which can be developed. In fact it may be used in conjunction with speed regulators or entirely independent thereof, and could be set to regulate the maximum speed, as well as regulating the compression at all intermediate points.

In starting an engine (as is well known) the same adjustment which is used when the engine is running at its normal high temperature is not satisfactory when the engine is running cold. For this purpose I provide a temperature control adjustment (preferably automatic) whereby the valve F in all its various adjustments of compression control through the cam G is nevertheless operated at different ranges. While this could be accomplished in various forms of mechanism, I have diagrammatically illustrated it as being carried out in the following manner: At its upper end the stem G² has an adjustable sleeve portion K which connects the two parts of the stem G² carried by the thermostat K'. The latter, through a pipe K², is subjected to the temperature of the water jacket A² so that as the temperature in the cylinder is increased, the heat developed will, through the water-cooling system, pass to the chamber K³ and expand the thermostat K'. This will lower the rod G² and adjust the pivot G' of the cam G downward. Therefore, when the sleeve H is raised by the centrifugal arms I² it will produce a lesser open adjustment of the valve F than when the thermostat is contracted. In order to permit of a manual adjustment of the cam G, I preferably provide the stem G² with a sleeve portion K which has a pin operating in the inclined groove K⁴. Therefore, as the sleeve K is rocked by the arm K⁵ it will increase or decrease the total length of the rod G² so

that manual adjustment of the pivot point G' is possible independent of the thermostatic adjustment. While I have shown and described the valve F as being separate from the valve E it is of course possible that the two valves might be combined in one and various other changes made in the details of construction (which is illustrated mostly diagrammatically) without departing from the scope of my invention.

One important feature of my invention that I particularly desire to point out is the fact that an engine equipped with my compression regulator system cannot be injured by the operator suddenly throwing the throttle valve E to a wide open position. If he does so with my improved construction it will be impossible for the engine to receive a charge that will give a higher compression than that desired at the particular speed at which the engine is turning. This is due to the fact that the valve F is automatically adjusted to restrict the opening past the same to a degree where the amount of mixture reaching the engine cylinder can only produce the maximum degree of compression desired at any speed. However, as the speed of the engine increases the valve F will be automatically adjusted to a further open position so as to permit the amount of air and gas mixture to flow to the engine cylinders which will give the desired degree of compression at this higher speed. Thus I am enabled to use an abnormally small clearance space and at the same time to limit the compression at all speeds so that the danger of injuring the engine by the operator suddenly adjusting the hand-controlled throttle to wide open position is avoided. The invention, however, in its broader aspects is not limited to the two forms of mechanism shown nor to the construction and combination of parts and operations except as ultimately set forth in the claims.

What I claim as my invention is:

1. In an internal combustion engine, the combination with the engine cylinder, of mechanism associated therewith for automatically increasing the degree of compression in said cylinder in accordance with the increase in the speed of the engine.
2. In an internal combustion engine, the combination with the engine cylinder, of mechanism associated therewith for automatically increasing the degree of compression in said cylinder in accordance with the increase in the speed of the engine and to adjust the range of compression regulation in accordance with changes in the engine temperature.
3. In an internal combustion engine, the combination with the engine cylinder and a piston working therein having a constant minimum clearance space, of mechanism connected therewith for automatically in-

creasing the degree of compression in said cylinder in accordance with the increase in the speed of the engine.

4. In an internal combustion engine, the combination with the engine cylinder, of a valve controlling the supply of combustible mixture to said cylinder and an automatic-

ally governed valve independent of the first-mentioned valve for increasing the maximum amount of combustible mixture 10 in said cylinder in accordance with the increase in the speed of the engine.

In testimony whereof I affix my signature.

PHELPS M. FREER.
